INVENTION.
Horace Coleman Jr.
by Frank L. Clark attorney.

UNITED STATES PATENT OFFICE.

HORACE COLEMAN, JR., OF ELLSWORTH, KANSAS.

DESIGN FOR A BOTTLE.

SPECIFICATION forming part of Design No. 20,629, dated March 24, 1891.

Application filed February 18, 1891. Serial No. 381,971. Term of patent 7 years.

To all whom it may concern:

Be it known that I, HORACE COLEMAN, Jr., of Ellsworth, in the county of Ellsworth, State of Kansas, have invented and produced a new and original Design for Bottles, of which the following is a specification, reference being had to the accompanying drawings, in which—

Figure 1 is a perspective view of my newly-designed bottle. Fig. 2 is a side view of the same.

The bottle constituting my design is of the ordinary die or cube shape, having six flat sides or faces of equal size, the ends of the corners being rounded off a sufficient distance, so as to cause the said faces or sides to represent circles.

A is the body of the bottle, which is a cube or die having six oppositely-arranged sides or faces of equal size. The ends of the corners C are rounded off, so as to form triangular convex faces B. It will thus be seen that by rounding the ends of the corners of the sides or faces the top, sides, and bottom of the bottle will represent circles.

The neck D of the bottle projects at an angle from one of the rounded corners, as seen in the drawings. 25

Each of the six sides or faces of the bottle has formed upon it depressions a, as seen in the drawings. 30

The leading feature of my design consists of the cube or die shaped body having the ends of the corners rounded off to cause the top, sides, and bottom of the bottle to represent circles, and each of said circular sides or 35 faces having thereon depressions, as shown and described.

What I claim is—

The design for bottles herein shown and described. 40

In testimony whereof I have hereunto signed my name this 16th day of February, 1891.

HORACE COLEMAN, JR.
